MOTOR DRIVE FOR PRINTING AND ISSUING MACHINES

Thomas A. Keen, San Mateo, and James Kilburg, Redwood City, Calif., assignors, by direct and mesne assignments, of one-half to said Keen and one-half to Hannah M. Smith, Chicago, Ill.

Original application August 7, 1939, Serial No. 288,840. Divided and this application October 13, 1941, Serial No. 414,828

4 Claims. (Cl. 74—74)

The present invention relates to a motor drive and transmission mechanism for a ticket printing and issuing machine or the like, and this application is a division of our co-pending application entitled "Ticket printing and issuing machine," filed August 7, 1939, Serial No. 288,840.

In the said co-pending application we disclose a ticket printing and issuing machine which functions at the will of the operator to print tickets bearing data such as the number of a race and entry therein, the date, and a code character identifying the ticket with the particular race for which it was printed. In this machine, as in substantially all machines designed for the issuance of tickets or receipts for bets under the parimutuel system required by law in many territories, the number to be printed upon the ticket, which signifies the entry upon which the bet has been made, is selected by the operator who, at the time of such selection, also initiates an operation of the machine to print and issue the proper ticket. In the machine disclosed in the application of which the present application is a division, a numbered keyboard is provided for selection of the number of the entry to be printed on the ticket and depression of any one of the keys on such board effects positioning of a cam which is thereafter power driven to control the position of a printing head bearing numbers corresponding to the numbers on the keys. This printing head is rotated by power to bring it into position wherein its type, selected by depression of a key, will effect printing when a platen, also power driven, is moved toward the printing head to press against it a ticket strip to be printed upon. Movement of this ticket strip is also effected by power, as are the movements of a coordinated ticket strip advancing mechanism and a shear which severs the ticket from the strip after the printing has been accomplished. A power driven ejection roller operates to discharge the printed and severed ticket from the machine.

It is the object of the present invention to provide a motor drive and transmission for use in a machine of this general character which will produce the necessary motion in an efficient, rapid, relatively silent and perfectly timed manner for operating the selector cams which control the positioning of the printing head; for rotating the printing head to effect selection of type to be printed, and for returning the same to its normal position; for imparting printing motion to the platen; for advancing the ticket strip after the printing has been accomplished; and for cutting off and ejecting the printed ticket.

A further and more specific object of the invention is to provide, in a power transmission of this kind, a Geneva type of movement for imparting uni-directional movement of a rotary shaft to alternate movement in opposite directions of a second shaft with intermediate dwell periods, and with the speed of the movement between said dwell periods occurring at a constant rate, as distinguished from the decelerated and accelerated motion produced by conventional Geneva movements.

Further objects and advantages of the invention are made apparent in the following specification, wherein the motor drive and transmission of the present invention are disclosed in a typical installation.

While the present disclosure illustrates the application of this invention to a specific type of ticket printing and issuing machine, it is capable of application to other machines, and the specific structure and functions of this machine are not to be considered as a part of this invention, as the same may be applied to various types of machines where similar power driven movement is required.

In the drawings:

Fig. 1 is a side elevation of a ticket printing and issuing machine, typical of the kind in which the motor drive of the present invention may be used, with a portion of the casing broken away to disclose portions of the motor drive mechanism;

Fig. 2 is a view somewhat similar to Fig. 1, with the drive mechanism illustrated in section taken on line II—II of Fig. 3;

Fig. 3 is a view of the drive mechanism looking up from the bottom of the machine;

Fig. 4 is a side elevation of Geneva gears which form a part of the drive mechanism; and

Fig. 5 is a side elevation of another of said gears.

The machine in which the present motor drive is illustrated is shown in the drawings as comprising a main case 10 on top of which is disposed a cover 11 which encloses the printing mechanism disposed above the case and beneath which is a motor housing 12. Beneath the cover 11 is a generally cylindrical printing head mounted for rotation with a shaft 17 which carries peripherally spaced type characters 37. The printing head is rotatable by means of the shaft 17 to bring any selected one of the type characters 37 to a position directly beneath the shaft 17, which is its printing position.

A selector stop plate 54, associated with the portion of the printing head which carries the

type characters 37, cooperates with the stop finger 49 carried on a differentially adjustable block 121, mounted for sliding movement to and away from the axis of the selector plate 54 in a track 122, and controlled by a lever 123 which is pivotally supported at 125. The lower end of this lever is connected with a link 135 which extends forwardly in the machine and is controlled in its movement by means of a selector mechanism not shown, which operates under influence of a bank of keys 120 which are numbered to correspond with the type characters 37 on the printing head so that depression of any key effects control of the movement of the printing head to bring the correspondingly numbered type character into printing position.

When the proper character has been positioned for printing, a printing platen 350, which is supported on a frame 351, is swung upwardly to press a ticket strip 291 into contact with the type character and effect printing. The frame 351 is supported on arms 352 (see Fig. 3) which extend rearwardly and are pivotally supported on a shaft 330. Fingers 353 depend from the arms 352 and present low ends positioned for engagement by cams, presently to be described, which impart the necessary swinging movement to the platen frame.

The ticket strip 291 enters the machine on the bottom between guide plates 300 and 301 and is led over a feeding drum 302 (see Fig. 3) which is provided with spaced feeding teeth 303 which register with perforations on the ticket strip so that upon rotation of the drum, the strip is advanced and the end which underlies the printing head and has been printed upon, is projected to a position where it may be sheared and ejected from the machine.

The printing drum 302 is fixed to a shaft 323 upon which a gear 322 is rotatably mounted. A ratchet 325 is also secured to this shaft so that pawl 326, pivoted to the side of the gear 322, engages with this ratchet to advance the same and the ticket feeding drum, to feed the ticket strip one ticket length upon rotation in a counter-clockwise direction of a quadrant 321, which meshes with the gear 322. Upon clockwise rotation of the quadrant, which occurs prior to the clockwise movement just mentioned, the pawl 326 rides over the ratchet 325 and a spring pawl 328 engages the ratchet to prevent reverse movement thereof. This feeding movement of the ticket strip follows the ticket printing operation so that the newly printed ticket at the end of the strip is fed through an opening 308 in a shear head 309, which carries a blade 310 adapted to cooperate with a hardened insert 311 to shear the ticket.

The shear head is supported for rocking movement on shaft 330 and carries a tail 331 which is engageable by a cam, as hereinafter described, to rock the shear head and cause the blade 310 to shear the ticket from the strip positioned below the shear head 309, and normally tends to swing it upwardly about its pivotal support on the shaft 330. An idler roller 334 is also carried by the shear head 309 and upon rocking movement thereof presses the ticket into engagement with a constantly rotating ejector roller 312, so that the sheared ticket is advanced through a delivery slot 313.

The mechanism thus far briefly described is identical with that illustrated in application Serial No. 288,840, of which this is a division, and forms no part of the present invention other

than that it is illustrative of the type of mechanism with which the present motor drive and transmission mechanism is intended to be used.

The power is supplied, as illustrated in Fig. 1, by a continuously operating electric motor 400 enclosed in the motor housing 12 which depends from the bottom of the main case 10. Through suitable reduction gears enclosed in a housing 401, at one end of the motor, a sprocket 402 is driven, and through a chain 403 leading over an idler roller 404, continuous rotation is imparted to a sprocket 405 secured to the outer member of a clutch 406 (see also Fig. 3). The inner or driven member of this clutch is fixed to and rotatable with the main shaft 333. The clutch 406 is a single cycle clutch, preferably of the over-running roller type, described in detail in our co-pending application above referred to, though other types of single cycle clutches may be used in its place. Upon initiation of a ticket printing operation, the clutch is engaged through mechanism hereinafter described for a single cycle to impart a single complete rotation to the main shaft 333. From the rotation of this shaft is taken the power for performing all of the principal functions of the ticket printing and issuing machine.

Referring to Fig. 3, in which the cam shaft 333 is illustrated as viewed from the bottom of the machine, a sprocket 407 is shown as keyed to the shaft and as driving a chain 408 which is trained over and drives a sprocket 409 on a shaft 410, which shaft also carries a gear 411 meshing with a gear 412 keyed to a shaft 413 upon which is mounted the ejector roller 312 (see Fig. 2). The main shaft 333 also carries (see Figs. 2 and 3) a pair of platen actuating cams 354 which, upon rotation of the shaft 333, engage the fingers 353 of the platen frame, thus swinging the platen upwardly about its pivot 330 to printing position.

The ticket shearing knife is actuated by a cam 332 also carried on the shaft 333. This cam engages upon rotation with the tail 331 which depends from the shear head, rocking the head about its pivot 330 to shear the ticket strip and at the same time to effect ejection of the sheared ticket by pressing it between the idler 334 and the rotating ejecting roller 312.

A counter-shaft 320 supports the quadrant 321 which drives the strip feeding mechanism above described, and which also imparts timed rotation in opposite directions to the shaft 17, which supports the printing head. For the latter purpose, the shaft 17 carries a gear 21 meshing with an idler gear 21a which, in turn, meshes with the quadrant 321. This counter-shaft 320 is connected with the main shaft 333 through the medium of a double-acting Geneva movement mounted on another counter-shaft which, for convenience, will be referred to as the Geneva shaft 414. The outer end of this Geneva shaft 414 carries a sprocket 415 (see Fig. 3), which drives a chain 416, which chain leads to the forward end of the machine, and transmits power to the selector mechanism, not shown, which functions under control of the keys 120.

The Geneva movement, interposed between the main shaft 333 and the counter-shaft 320, is especially designed to transmit the uni-directional motion of the main shaft to rotation in opposite directions of the counter-shaft with intermediate dwell periods. As shown in Figs. 2 and 3, the main shaft carries a gear 425 meshing with a gear 426 which rotates freely on the Geneva shaft 414 and which carries with it a Geneva driving

member 427 adapted to drive a Geneva driven member 428 in one direction. Also carried by the main shaft is a gear 429 which, through a pinion 430, drives a gear 431 fixed to the Geneva shaft and carrying a Geneva member 432 like the member 427, but rotating in the opposite direction to impart such rotation to the Geneva driven member 428.

The construction of the driving and the driven members of the Geneva movement is illustrated in Figs. 4 and 5. In Fig. 4, the driven member 428 is shown in registry with the driving member 432. The driving member 427, shown in Fig. 5, lies directly behind the member 432 and rotates oppositely thereto and in a different phase position, its relative phase position being that shown in Fig. 5. The driven member 428 comprises a gear segment 435 at opposite ends of which are recesses 436 and 437 cut arcuately to the pitch diameter of the driving members 427 and 432. Each of these driving members has a set of gear teeth 438 cut to mesh with the teeth 435 of the driven member during a portion of their rotation and at both ends of the teeth 438 are peripheral surfaces 439 and 440 formed on the pitch diameter of the teeth 438 for registry with the recesses 436 and 437 on the driven member to cause the same to dwell when the teeth of the driving members are not in driving engagement with the teeth of the driven member. The remainder of the periphery of each of the driving members is cut away for clearance, as shown at 441, to permit free rotation of the driven member while the other driving member is in mesh with the driven member and rotating it.

As viewed in Fig. 4, the driving member 432 rotates continuously in counter-clockwise direction during rotation of the main shaft. In the position shown, its teeth 438 have just left their mesh with the teeth 435 of the driven member, during which mesh the driven member was rocked in a clockwise direction to impart clockwise rotation to the shaft 320 which, as has been described, rotates the shaft 17 of the printing head to permit selection of the type to be printed. In the position shown, the surface 439 of the driving member registers with the recess 436 of the driven member causing it to dwell until the time when the teeth of the driving member 427, which is moving in clockwise direction, will mesh with the teeth 435 of the driven member, imparting to it and the shaft 320 rocking movement in a counter-clockwise direction, which is effective to return the main shaft of the printing head to its normal position and to advance the ticket strip through the medium of the quadrant 321, gear 322, pawl 326, and ratchet 325 which, as previously described, rotates the feed drum 302. The driving members 427 and 432 are identical in shape but operate in opposite directions to rock the shaft 320 intermittently in opposite directions and to cause it to dwell between its rocking motions.

The Geneva movement, just described, provides a decided advantage in a machine of this character because it is considerably smaller in over-all dimensions than a conventional pin and slot Geneva that would be required to perform this function, and the rocking movement of the driven member is maintained at a constant speed while the gears of the Geneva members are in mesh, whereas in the conventional pin and slot type of Geneva, the movement of the driven member decelerates and accelerates during each operation, due to the fact that the pin of the driving

member varies in its position with respect to the center of the driven member.

The cycle of operation of the power transmission mechanism above described is controlled by the operator of the machine and is preferably initiated by depression of any one of the selector keys 120. The main clutch 406 is normally disengaged but permitted to engage for a single cycle to impart a complete rotation to the main drive shaft 333 once for each ticket printing operation of the machine. This clutch, as illustrated in Fig. 1, includes a lug 445 which, when detained, prevents engagement of the clutch. The hooked end 446 of a lever 447 pivotally supported at 448, normally engages behind this lug to prevent engagement of the clutch. Upon raising of the hooked end of this lever momentarily to clear the lug 445, the clutch engages and drives the main shaft 333 until the lug 445 makes a complete revolution and again comes into contact with the end of the lever.

Forwardly of the pivot 448, the lever carries a downwardly extending pivoted pawl 449; a spring 450 urges the pawl to the left and to a position substantially perpendicular to the lever 447, at which position it stops by reason of a shoulder 451 which engages with the bottom of the lever. The pawl thus normally assumes the position illustrated, but is free to swing to the right against the tension of the spring 450.

A solenoid 452 has a retractable armature 453 pivoted to a lever 454 which is, in turn, pivoted as at 455 at one end and engages with the pawl 449 at its opposite end. A spring 460 tends to hold the armature and the lever 454 upwardly in a position limited by a stop tail 461 on the lever. The solenoid 452 is energized by closing of a switch (not shown) which, as stated, is preferably closed on depression of any one of the keys 120. Energization of the solenoid retracts the armature which, through the lever 454 and pawl 449, swings the lever 447 about its pivot 448 to raise its end 446 free of the lug 445. The end of the pawl 449 swings away from the lever 454 during this operation, its movement being on an arc struck from the center of the pivot 448. Consequently, a single cycle operation is assured even though the operator should fail to release the key which effects energization of the solenoid.

If, due to such improper operation, the armature and lever 454 remain in their down position, the spring 450 returns the pawl 449 and the lever 447 to normal and, in being returned, the pawl 449 rides over the end of the lever 454. Upon subsequent de-energization of the solenoid, the lever 454 will rise about its pivot under tension of the spring 460 and in so doing its end will swing the pawl out of the way and come to rest in the position illustrated. Thus, closing of the switch which energizes the solenoid 452 effects an engagement of the clutch 406 for a single cycle during which the transmission will distribute power to the various parts of the machine to complete a single ticket printing and issuing operation.

To insure against rebound or any reverse movement taking place through the clutch, the cam 332 (see Fig. 2) which operates the shear arm at the end of the cycle of operation, comes to rest in the position shown, directly beneath the tail 331 of the shear head, which tail locks it, and consequently the shaft 333, against reverse movement. This serves to prevent chattering and to reduce friction between the clutch parts while it is disengaged or in its idling position.

Having thus described our invention, what we claim and desire to secure by Letters Patent is:

1. In a power transmission for a ticket printing machine or the like, mechanism for transmitting rotary motion to alternate opposite movements which comprises a driven member, and a pair of identical driving members rotatable in opposite directions on a common axis and having gear teeth arranged to mesh during a part of their rotation with the teeth on the driven member, each of said driving members having peripheral portions registering with arcuate recesses on the periphery of the driven member at timed intervals to cause the driven member to dwell between its movement in opposite directions.

2. In a power transmission for a ticket printing machine or the like, mechanism for transmitting rotary motion to alternate opposite movements which comprises a driven member, a pair of identical driving members rotatable in opposite directions on a common axis and having gear teeth arranged to mesh during a part of their rotation with the teeth on the driven member, each of said driving members having peripheral portions registering with arcuate recesses on the periphery of the driven member at timed intervals to cause the driven member to dwell between its movement in opposite directions, and each of said driving members having a relieved space on its periphery to clear the teeth of the driven member to permit it to be independently driven by the other driving member.

3. In a machine of the character described, mechanism for transmitting continuous rotary movement to intermittent rotary movement in opposite directions which comprises a rotatable driven member having gear teeth formed along a portion of its periphery and an arcuate recess adjacent said teeth, a rotary drive member having teeth adapted to mesh with the teeth of the driven member and a segment of its periphery adapted to register with the recess in the periphery of the driven member to cause it to dwell during a portion of the cycle of the driving member, and a second similar drive member rotating opposite to the first and meshing with the driven member after its dwell period.

4. In a power transmission for a ticket printing machine or the like, mechanism for transmitting rotary motion to alternate opposite movements which comprises a rotatable segmentally toothed driven member, a pair of segmentally toothed drive members rotatable on a common axis in opposite directions and engaging with the teeth of the driven member to drive it alternately in opposite directions, said driven member having arcuate recesses, one adjacent each end of its toothed portion, formed at the pitch diameter of the driving members, and said driving members having peripheral surfaces at their pitch diameters to register with said recesses and compel the driven member to dwell between its driven movements.

THOMAS A. KEEN.
JAMES KILBURG.
